[57] CLAIM

The ornamental design for a pair of disposable sandals, as shown and described.

DESCRIPTION

FIG. 1 is a perspective view of the right sandal of the pair of disposable sandals of the subject invention;

FIG. 2 is a left side view of the sandal of FIG. 1;

FIG. 3 is a right side view of the sandal of FIG. 1;

FIG. 4 is a top view of the sandal of FIG. 1;

FIG. 5 is a bottom view of the sandal of FIG. 1;

FIG. 6 is a front view of the sandal of FIG. 1;

FIG. 7 is a rear view of the sandal of FIG. 1;

FIG. 8 is a perspective view of the sandal of FIG. 1, laid flat;

FIG. 9 is a top view of the sandal of FIG. 1, laid flat;

FIG. 10 is a perspective view of another preferred embodiment of the right sandal of the pair of disposable sandals of the subject invention;

FIG. 11 is a top view of the sandal of FIG. 10;

FIG. 12 is a front view of the sandal of FIG. 10;

FIG. 13 is a rear view of the sandal of FIG. 10;

FIG. 14 is a perspective view of the sandal of FIG. 10, laid flat; and,

FIG. 15 is a top view of the sandal of FIG. 10, laid flat;

All of the figures show the sandal suitable for the right foot; that for the left foot are mirror images of the figures shown.
